UNITED STATES PATENT OFFICE.

JACOB D. SCHAKEL, OF CHICAGO, ILLINOIS, ASSIGNOR TO ELEVATOR COMPANY OF AMERICA, OF CHICAGO, ILLINOIS, A CORPORATION OF ILLINOIS.

ELEVATOR-DOOR-LOCKING DEVICE.

Application filed November 6, 1922. Serial No. 599,374.

To all whom it may concern:

Be it known that I, JACOB D. SCHAKEL, a citizen of the United States, residing at Chicago, in the county of Cook and State of Illinois, have invented a certain new and useful Improvement in Elevator-Door-Locking Devices, of which the following is a full, clear, concise, and exact description, reference being had to the accompanying drawings, forming a part of this specification.

My invention relates to an elevator door locking device that is particularly adapted for use with electrically operated elevators.

It is a purpose of the invention to provide an elevator door locking device which will keep the door locked at all times except when the elevator is opposite the floor at which the door is located and the elevator is stopped. It has been found that where automatic elevators are used, it is quite often the case that the person who has pushed the button to bring the elevator to the floor at which the person is located does not receive the elevator, because a person at another floor that the elevator must pass, by manipulating the lock properly, can open the door and break the operating circuit of the elevator. This is due to the fact that all automatic electric elevators are provided with means for breaking the operating circuit when any door is open.

It is the purpose of the invention to prevent the person who is not entitled to the elevator to stop the same in this manner, and in order to accomplish this purpose a device is provided which will unlock the door only when the operating current has been shut off by the control device, and the car is opposite a floor. In the form shown the means for accomplishing this purpose comprises a lever pivoted intermediate the ends thereof upon a suitable support, said lever having a shoe thereon which is adapted to engage with a roller that acts to move a locking member out of locking position. The shoe is normally held in a position so that it will not contact with the rollers when the operating current is on.

It is a further purpose of the invention to provide means for holding said shoe in a position so as to not engage the lock operating rollers which comprise a solenoid which is connected in series in the operating circuit, so that when the operating current is on the solenoid will hold the lever in

such a position as to have the shoe out of roller contacting position. The rollers are, of course, located in such positions in the shaft as to be engaged by the shoe which is carried by the elevator when the elevator is substantially aligned with the floor adjacent which the roller is located.

It is still a further purpose of the invention to provide a door locking means which is mechanical in operation, and which is made up of but few simple moving parts, and in which the unlocking device is held in inoperative position by electrical means in circuit with the operating circuit for the elevator car.

Other objects and advantages of the invention will appear as the description of the accompanying drawings proceeds. However, I desire to have it distinctly understood that I do not intend to limit myself to the exact details shown or described, but that I intend to include as part of my invention all such obvious changes and modifications of parts as would occur to a person skilled in this art and as would fall within the scope of the claims.

In the drawings:

Fig. 1 is a view in side elevation of a portion of the elevator framework showing my improved door unlocking device mounted thereon and showing one of the door unlocking devices cooperating therewith located at one of the floors;

Fig. 2 is a fragmentary face view of an elevator door showing my improved lock applied thereto;

Fig. 3 is a side elevation of the door unlocking device carried by the elevator;

Fig. 4 is a bottom plan view thereof;

Fig. 5 is a diagram of the circuit connections used in the door locking system;

Fig. 6 is a face view of a portion of a door showing a slightly different form of locking device applied thereto; and

Fig. 7 is an end view of the device shown in Fig. 6.

Referring in detail to the drawings, in Fig. 1 is shown a portion of an elevator framework comprising the uprights 10 and the transverse beams 11 to which are secured the bracket members 12 and the braces 13 for supporting a door lock actuating device, which comprises a base 14 having a vertically extending member 15 thereon which is provided with the spaced ears 16 and 17, 110

2
between which is mounted the shaft or pivot pin 18, upon which a lever 19 is adapted to swing as a pivot. The member 19 is provided with a pair of spaced arms 20 and 21, between which is mounted a shoe 22, said shoe having the cam-like curved end portions 23 so as to assure that the rollers 24 having a rubber facing or tread 25 engage always with the same side thereof. Said rollers 24 are mounted adjacent each of the floors at which the elevator stops and are each mounted on a shaft 26 which is journaled in a lever 27 pivotally mounted at 28 on a base plate 29, which base plate is secured to any suitable securing means, such as the members 30, to some portion of the elevator shaft or hatch. The plate 29 is provided with an apertured ear 31 through which the set screw 32 having the nuts 33 thereon extends. The screw 32 is adapted to engage with the end portion 34 of the lever 27 so as to limit the movement thereof in one direction.

The member 27 is also provided with an extension which extends beyond the shaft 26, said extension having an opening 35 in the end thereof for receiving a flexible member, such as a chain 36. The chain 36 is provided with a turn buckle 37 for adjusting the length thereof, and is connected at the end thereof, opposite the end engaging with the opening 35, with an eye in the end of the member 38 mounted on the shaft 39, said shaft 39, referring now to Fig. 2, being mounted in suitable brackets 40 which are mounted in any suitable manner in the hatch, said shaft 39 having a collar 41 thereon which is provided with a finger or latching member 42 which is adapted to engage in a latch plate 43 provided on the door 44, the door shown being a sliding door, and it will be obvious that when the member 42 is seated in the recess 45 in the plate 43, the door will be held effectively against movement, the member 42 acting as a stop to prevent such movement. The member 42 is normally held in position in the notch or recess 45 by means of the torsion spring 46 having one end thereof mounted in the collar 47 keyed to the shaft 39 and the other end thereof mounted in the bearing member 40.

Suitable collars 48 are provided to prevent endwise movement of the shaft 39. It will be seen that if the shoe 22 engages with the roller 25, the member 27 will be thrown to the right in Fig. 1, and the flexible member 36 will be pulled so as to swing the arm 38 in a counterclockwise direction in Fig. 1, thus disengaging the stop member 42 from the plate 43.

Suitable means has been provided whereby such an action will only take place when the operating current has been shut off. Said means comprises a solenoid 49 mounted

on the base 14 and having an armature 50 which is pivotally connected with an eye 51 on the rod 52 connected with a rod 53 by means of a turn buckle 54 for properly adjusting the length of the link comprising the members 52, 53 and 54, said rod 53 being provided with an eye 55 mounted on the pivot pin 56 extending across between the arms 57 of the bifurcated portion of the rearwardly extending arm 58 of the lever 19, said arm 58 having secured to the extreme end portion thereof the tension spring 59, the other end of which is connected with an ear 60 provided on a threaded member 61 passing through an apertured ear 62 in the base 14, said member 61 having nuts 63 threaded thereon for adjusting and locking the member 61 so as to obtain any desired tension on the spring 59.

The solenoid 49 in the form shown in Fig. 4 operates so as to turn the lever about the pivot 18 in a clockwise direction, that is, the armature 50 is moved outwardly so as to push on the lever arm 58. Accordingly when the solenoid 49 has current passing therethrough, the shoe 22 is held away from the roller 24 as shown in dotted lines in Fig. 4. However, if there is no current passing through the solenoid when the operating current is shut off, the spring 59 moves the lever to the full line position shown in Fig. 4, so as to cause the shoe 22 to contact with the roller 24 to move the stop member to door locking position. This action takes place substantially instantaneously due to the fact that the spring 59 is placed under tension when the solenoid is operated to hold the lever in such a position that the shoe is out of the path of the rollers.

The lever arm 20 is provided with a lug 64 which is adapted to engage with a stop pin 65 mounted in the web 66 and adjustable therein, said stop pin limiting the movement of the lever 20 in one direction. In order to provide for substantially a noiseless operation of the device, a compression spring 67 is mounted between the lug 68 on the lever 20 and the socket member 69 provided on the bolt 70 adjustably mounted in the web 66 and held in adjusted position by the nut 71.

Fig. 5 shows the arrangement of the electrical connections diagrammatically. In said figure the numeral 72 represents a starting switch interposed between one of the line wires 73 and the motor 74 that operates the elevator car. Interposed between the other line wire 75 and said motor is the solenoid 49 which operates the armature 51 connected with the lever 20 having a shoe 22 thereon, as previously described. It will be seen that when the switch 72 is in the position shown in Fig. 5, there will be no current flowing through the motor 74

nor through the solenoid 49 and the shoe 22 will be in position to engage with the roller 24, while if the switch 72 is in engagement with any one of the contact points 5 76, 77 or 78, the circuit will be closed, the solenoid 49 will be energized and the shoe 22 will be withdrawn so that the same will pass by the various rollers 24 without engaging with the same. As the shoe does 10 not engage with the rollers, except when operation of the lock is to take place, there will be no noise due to the shoe passing into and out of engagement with the rollers as the car moves up and down the shaft. 15 While an ordinary hand operated switch is shown in Fig. 5, it will be understood that the same principle will apply to an automatic switching device, such as provided in automatic elevators. In fact the 20 construction is particularly adapted for use with automatic elevators and the hand operated switch has been shown merely for the sake of simplicity. In the devices shown in Fig. 1 to 5 inclusive the door that is locked 25 is a sliding door. However, the invention can be applied as readily to a swinging door, and the form of the invention shown in Fig. 6 and 7 is particularly adapted for 30 swinging doors, but is also useful with sliding doors.

In the form of the invention shown in Figs. 6 and 7, the flexible member 36' is connected with one arm 79 of a bell crank lever 80 which is pivoted on the bracket 81 at 82, said bell crank lever being provided with an arm 83 having a pair of links 84 pivoted thereto to which is pivoted the stop pin 85 which is adapted to extend through an opening 86 in the channeled member 87 extending across the top of the elevator door. The pin 85 also extends through an opening 88 in the block 89 provided on the bracket 81, said bracket 81 being secured to the hatch adjacent the door in any desired manner. The end of the lever arm 83 extending beyond the links 84 is provided with an opening 90 through which the eye-bolt 91 extends, said eye-bolt being engaged by the tension spring 92, the other end of which 45 is mounted in a recess 93 in an extension 94 on the bracket 81. The tension of the spring 92 can be adjusted by means of the nut 95 provided on the eye-bolt 91, a locking nut 96 being also provided on said bolt. 50 An extension 97 is provided on the bell crank lever extending oppositely to the arm 83, said extension 97 being adapted to engage with a stop member 98 screwthreadedly 55 engaging in the apertured lug 99 on the bracket 81, said member 98 being adjustable in said lug and being provided with a nut 100 for holding the same in adjusted position. The operating mechanism in this 60 form of the invention is the same as that shown in Figs. 1 to 5 inclusive, and it will 65 be seen that when the roller 24 is engaged by the shoe 22 and the flexible member 36' is pulled to the left in Fig. 6, the spring 92 will be tensioned and the bolt 85 will be withdrawn from the opening 86 permitting 70 swinging of the door, or sliding thereof, as the case may be, to open the same. When the circuit is closed and the solenoid is energized, the shoe 22 will be withdrawn from the roller 24 and the pull on the member 75 36' will be removed. The tension spring 92 will then act to pull the bolt 85 downwardly and into engagement with the opening 86 locking the door against opening. 80 Having thus described my invention, what I desire to claim and secure by U. S. Letters Patent is:

1. The combination with a door, of a door locking device, comprising a member engaging said door to hold said door against movement, means for holding said member in door engaging position and means for moving said member out of door engaging position when the elevator is opposite the floor at which said door is located and the operating current for said elevator is cut off, said means comprising a lever pivotally mounted on said elevator intermediate the ends thereof. 90

2. The combination with a door, of a door locking device, comprising a member engaging said door to hold said door against movement, means for holding said member in door engaging position and means for moving said member out of door engaging position when the elevator is opposite the floor at which said door is located and the operating current for said elevator is cut off, said means comprising a lever pivotally carried by said elevator between the ends thereof and having a shoe rigidly mounted on one end thereof. 100

3. The combination with a door, of a door locking device, comprising a member engaging said door to hold said door against movement, means for holding said member in door engaging position and means for moving said member out of door engaging position when the elevator is opposite the floor at which said door is located and the operating current for said elevator is cut off, said means comprising a lever pivotally carried by said elevator between the ends thereof and having a shoe rigidly mounted on one end thereof, and means in the hatchway with which said shoe engages operatively connected with same member. 110

4. In an elevator door lock, a member engaging the door to lock the same against movement, and means for moving said member out of locking position, comprising a pivoted lever carried by the elevator, means operatively connected with said member mounted in the elevator shaft, a solenoid for holding said lever in a position 120 130

free of said means when the elevator operating current is on, and means for swinging said lever about its pivot into position for the end thereof to engage said means mounted in said shaft.

5. In an elevator door lock, a member engaging the door to lock the same against movement, and means for moving said member out of locking position, comprising a pivoted lever carried by the elevator, a roller operatively connected with said member mounted in the elevator shaft, a solenoid for holding said lever out of roller engaging position when the elevator operating current is on, and means for swinging said lever about its pivot into roller engaging position, said solenoid and means being on one side of said pivot and said lever engaging said roller on the other side thereof.

6. In an elevator door lock, a member engaging the door to lock the same against movement, and means for moving said member out of locking position, comprising a pivoted lever carried by the elevator, a roller operatively connected with said member mounted in the elevator shaft, a solenoid for holding said lever out of roller engaging position when the elevator operating current is on, and spring means for swinging said lever about its pivot into roller engaging position.

7. In an elevator door lock, a member engaging the door to lock the same against movement, means for normally holding said member in locking position and means for moving said member to unlocking position comprising a lever mounted in the elevator shaft in predetermined relationship to a floor, a roller thereon, a second lever pivotally mounted on the elevator between the ends thereof, a shoe rigidly mounted on one end of said lever adapted to engage with said roller, means for holding said lever in roller engaging position, and means adjacent the other end of said lever for holding said lever out of roller engaging position when the elevator operating current is on.

8. In an elevator door lock, a member engaging the door to lock the same against movement, means for normally holding said member in locking position and means for moving said member to unlocking position comprising a lever mounted in the elevator shaft in predetermined relationship to a floor, a roller thereon, a flexible connection between said member and said lever, a second lever pivotally mounted on the elevator, means for holding said second lever in roller engaging position and means for holding said lever out of roller engaging position when the elevator operating current is on.

9. In an elevator door lock, a member engaging the door to lock the same against movement, spring means for holding said member in locking position, and means acting against the tension of said spring to move said member to unlocking position, comprising a lever, a flexible connection between said lever and said member, a roller on said lever, a lever on the elevator having a shoe rigidly mounted on one end thereof, spring means for holding said lever in a position so that said shoe will engage said roller, and means for holding said lever with said shoe out of roller engaging position.

10. In an elevator door lock, a member engaging the door to lock the same against movement, spring means for holding said member in locking position, and means acting against the tension of said spring to move said member to unlocking position, comprising a lever, a flexible connection between said lever and said member, a roller on said lever, a lever on the elevator having a shoe rigidly mounted on one end thereof, spring means for holding said lever in a position so that said shoe will engage said roller, and a solenoid energized by the operating current for holding said lever with said shoe out of roller engaging position.

In witness whereof, I hereunto subscribe my name this 7th day of October A. D., 1922.

JACOB D. SCHAKEL.
